MOUTH OPENING AND CLOSING STRUCTURE FOR HANDBAGS

Dewey R. Spilman, Albuquerque, N. Mex.

Application July 16, 1951, Serial No. 236,880

1 Claim. (Cl. 150—11)

1

This invention relates to improvements in receptacles and particularly to open-top handbags, the primary object being to provide opening and closing structure for the handbag to facilitate quick and easy access to the contents thereof.

It is the most important object of the present invention to provide a pouch-like handbag of flexible material provided with an open-top and having a peripheral row of openings formed therein to receive a draw-cord or like closing structure, together with opposed means received by certain of such openings for facilitating opening of the bag against the action of the draw-cords.

A further object of this invention is to provide a handbag as above set forth, wherein the closing means for the bag comprises a pair of opposed loops both completely surrounding the bag adjacent its open top and both threaded through all of the openings of the bag, together with a pair of opposed secondary loops threaded through certain of the openings for facilitating opening of the bag as the secondary loops are moved apart.

These and other objects will be made clear or become apparent as the following specification progresses, reference being had to the accompanying drawing, wherein:

Figure 1 is a side elevational view of mouth opening and closing structure for handbags made pursuant to the present invention.

Fig. 2 is a perspective view of the handbag showing the same in the open condition; and

Fig. 3 is an enlarged, cross-sectional view taken on line III—III of Fig. 2 looking in the direction of the arrows.

The handbag illustrated in Figs. 1 to 3 inclusive of the drawing is broadly designated by the numeral 10 and while its shape and contour may vary from its pouch-like nature, it is to be preferred that the same have an open top 12 and constituting the sole means of access to the interior thereof.

Bag 10 is made entirely from flexible material that may include various types of leather, fabric or the like and when the same is in the open condition, its cross-sectional contour may either be cylindrical or elliptical as shown in Fig. 3 of the drawing, depending upon the shape or type of bag desired.

A continuous row of relatively small, spaced-apart openings 14 is provided in the bag 10 adjacent to, but spaced slightly below, the open top 12 thereof for receiving the openings and

2

closing structure hereof. Means for gathering together of the material forming the bag 10 adjacent the open top 12 in the manner illustrated by Fig. 1 of the drawing, includes a pair of continuous cord-like loops 16 and 18 of identical character. Both loops 16 and 18 completely surround the bag 10 and both are threaded through all of the openings 14 in the manner illustrated by Fig. 3 of the drawing.

10 Bight 20 of loop 16 is disposed adjacent one end of the bag 10 and the ends of the loop 16 extend beyond the opposite end of bag 10 and are preferably interconnected by a knot 22. Similarly, bight 24 of the loop 18 is disposed adjacent the opposite end of bag 10 and the ends of loop 18 that project beyond bag 10 at bight 20 are interconnected by a knot 26. It is appreciated that when the knotted ends of the loops 16 and 18 are grasped and moved apart, bights 20 and 24 will be moved toward each other and the bag 10 gathered at its open mouth 12 and closed as shown in Fig. 1 of the drawing.

Such construction makes it somewhat difficult to re-open the bag 10 to the condition shown in Figs. 2 and 3 of the drawing since it becomes necessary for the user to wedge his fingers into the bag 10 at the open mouth 12 thereof and attempt to cause the bights 20 and 24 to separate and thereby spread the open mouth 12 to the condition shown in Figs. 2 and 3.

Accordingly, there is provided a pair of secondary loops 28 and 30 at opposite ends of the bag 10 adjacent the bights 20 and 24 respectively. Each loop 28—30 is threaded through but one pair of openings 14, loop 28 extending through the openings 14 from which the knotted ends of loop 18 extend and conversely, the secondary loop 30 passes through the openings from which the knotted ends of loop 16 project.

40 In order to easily identify the secondary loops 28 and 30, the same are preferably relatively small and knotted as at 32 to threadably receive a perforated, decorative knob 34. It is now seen that when the bag 10 is in the closed condition as shown in Fig. 1 of the drawing, a user may easily and quickly find the secondary loops 28 and 30 by reaching for the knobs 34. Pulling of the knobs 34 away from each other operates to separate the bights 20 and 24 of primary loops 16 and 18 respectively, thereby opening the bag 10 as shown in Figs. 2 and 3 of the drawing. It is clear that neither the opening nor the closing means for the bag 10 will interfere with the use thereof for its intended purpose and that the loops 16, 18, 28 and 30 add to the attractiveness

of the handbag in addition to providing the utilitarian purposes above set forth.

Having thus described the invention what is claimed as new and desired to be secured by Letters Patent is:

In a handbag having an open top, pouch-like body of flexible material provided with a peripheral row of openings adjacent the uppermost marginal edges thereof, a pair of opposed primary loops, each loop being separate from the body and having a bight, the bights being in opposed relationship, each loop being threaded through said openings for gathering the body together, as the bights are moved toward each other, into folds adjacent said top thereof and to thereby close said top of the body, each bight spanning the distance between a respective pair of openings exteriorly of the body; and a secondary loop separate from the body and threaded through certain of said openings adjacent each bight respectively for spreading the body to unfold the same, and for moving said bights away from each other, as the secondary loops are moved away from each other, whereby to open said top of the body, each primary loop passing through

10
20
25

all of the openings, each secondary loop passing through one of said pair of openings and having a bight spanning the distance therebetween within the body, whereby to dispose portions of the body between the bights of the secondary loops, the bight of each secondary loop being threaded through the bight of a corresponding primary loop, whereby to transmit a direct pull on the primary loops when the secondary loops are moved apart to open the body.
